UNITED STATES PATENT OFFICE.

HENRY ST. G. LINDSAY, OF OTTAWA, ONTARIO, CANADA.

STOWING AND LOWERING BOATS.

1,052,351.

Specification of Letters Patent.

Patented Feb. 4, 1913.

Application filed June 1, 1912. Serial No. 701,054.

To all whom it may concern:

Be it known that I, HENRY ST. G. LINDSAY, a subject of the King of Great Britain, residing at Ottawa, in the Province of Ontario, Canada, have invented certain new and useful Improvements in the Stowing and Lowering of Boats, of which the following is a specification.

My invention relates to improvements in the stowing and lowering of boats on board ship as described in the present specification and illustrated by the accompanying drawings that form part of the same.

The invention consists essentially of a boat chock mounted through a swivel on a carrier provided with brake mechanism and carrying rollers whereby said carrier is adapted to run on rails or launching ways suitably secured to the ship deck; said rails being arranged transversely of said deck whereby, in combination with davits, boats can be lowered from one or both sides of a ship. The movement of the boats on the rails being controlled by said brake mechanism. Apertures in said rails adapted to receive "stops" for firmly securing the boats when not in use.

The object of my invention is to provide a new, simple, effective and inexpensive means for launching one or more boats from a ship under all conditions of weather.

A further object is to provide means for stowing a number of boats on portions of the deck otherwise not used and in such manner that, when required, they will be easily accessible and readily lowered, if necessary from both sides of the ship simultaneously.

With these and other objects in view reference is now had to the accompanying drawings in which like numerals of reference indicate corresponding parts in each figure, and in which,

Figure 1. is a plan view of a series of boats stowed side by side on rails extending transversely across the ship. Fig. 2. is a side elevation of a boat mounted on my device. Fig. 3. is an end view partly in section of my invention. Fig. 4. is an enlarged front view showing relative positions of roller and operating cam lever. Fig. 5. is a plan view of a rail with cleats or stops in position.

Referring to the drawings, 1 is the deck of the ship, 2 the boat and 3 davits.

4 are rails arranged transversely across the deck 1 and secured fixedly thereto in any suitable manner.

5 is the chock formed with a step-bearing 5' adapted to engage with the supporting pin 6" on the carrier 6. Said supporting pin forming a swivel with the chock. The top of the former being threaded to receive a lock-bolt if necessary to more firmly secure the latter. The carrier 6 is adapted to fit over, and on one side at 11, to overlap, the tread of the rail, traveling on same by means of the rollers 9-9' carried in said carrier on the axle 10. The other side of the carrier 6, is formed at 6' to carry a lever 7 and the friction roller 8, on the axle 8', forming a brake for said carrier; whereby its travel on the rail is fully controlled and regulated.

12-12' are cleats or stops formed with pins 13-13' adapted to engage with the apertures 14 in the rails. While here shown in Fig. 3 as one on each side of the carrier 6, two each side may be used with advantage. The boat being thus held more securely in position when not in use. These stops are provided with handling means in the form of rings for pulling them up when the boats are about to be lowered. The apertures 14 may be continued through the base of the rail if necessary.

To launch the boat, the stops 12-12' are first pulled out when the boat on its chock will slide down the rails quickly and smoothly by means of the rollers 9-9'. The length of the davits with suspending tackle being arranged the sliding will be accomplished without any jerky action. To check the boat in its travel or control its pace, so that it will not pass out too quickly, it is only necessary to apply the brake-mechanism by operating the lever 7, which in turn will operate the friction roller 8 against the under part of the rail. To replace the boats after being hoisted from the water, they are lowered on to the waiting chocks, each pair of same on being loaded, being moved up the rails and secured in their places by replacing the stops 14.

With my invention any number of boats that can be accommodated side by side on the rails may be lowered on either side of the ship, as required.

The brake-mechanism consists more particularly of the lever 7 adapted to engage

the square end of the axle 8'. Said axle being adapted to the eccentrically mounted roller 8, fixedly secured thereto said axle being provided at 8" with a suitable bearing to work in freely.

5 The operating handle of the lever 7 can be made detachable for more convenient storage, and is provided with a friction pin 15 to more securely retain it in position.

10 What I claim for my invention is:—

1. A device of the class described comprising launching-rails, chocks, with swivels, mounted on carriers, rollers in said carriers adapted to travel on said rails; one 15 side of the carrier overlapping said rail, a friction brake supported by the extended other side of the carrier; operating means for said brake; apertures in said rails

adapted to receive securing means for stops or cleats adapted to hold said chock-carrier 20 securely in position.

2. In a device of the class described the combination with launching rails of a chock mounted through a swivel on a carrier adapted to travel on said rails provided 25 with brake-mechanism whereby the travel of said chock is controlled.

In testimony whereof I have hereunto signed my name in the presence of two subscribing witnesses at the city of Ottawa, 30 Province of Ontario, this 18th day of May, 1912.

H. ST. G. LINDSAY.
